UNITED STATES PATENT OFFICE.

BERNARR MACFADDEN, OF LONDON, ENGLAND.

RAILWAY SYSTEM.

1,133,734.

Specification of Letters Patent. Patented Mar. 30, 1915.

Application filed September 24, 1914. Serial No. 863,400.

To all whom it may concern:

Be it known that I, BERNARR MACFADDEN, a citizen of the United States, and resident of London, England, have invented a certain 5 new and useful Improvement in Railway Systems, of which the following is a specification.

My invention relates to a railway system especially intended for use in buildings, especially intended for use in buildings, 10 poriums or the like for conveying passengers over the several floors, the essential feature of my invention consisting in the provision of means whereby passengers may enter a car on the ground floor of the building or 15 the like and be conveyed to another floor, or successively to a series of other floors, around which floor, or each of which floors, the car will be caused to traverse, and finally returned to the ground level.

20 To enable my invention to be fully understood I will describe the same by reference to the accompanying drawings, in which:—

Figure 1 is a diagrammatic perspective view illustrating an arrangement of the 25 tracks and lifts in connection with a building having five floors. Fig. 2 is a diagrammatic elevation illustrating an arrangement of the tracks in conjunction with the lifts and the electric operating gear. Fig. 3 is an 30 elevation showing the lower part of the elevating lifts with a car thereon and with an adjacent portion of the track and one of the contact devices. Fig. 4 is a plan of the same, the car being omitted. Fig. 5 is a plan view 35 of the car. Figs. 6 and 7 are sections on the lines 6—6 and 7—7, Fig. 3, illustrating the arrangement of the safety gear which is used in connection with the lifts. Fig. 8 is a diagram illustrating the controlling devices 40 in connection with a car motor. Fig. 9 illustrates diagrammatically an arrangement of multi-stage lift adapted to be used for lifting a plurality of cars at one movement and for lowering a plurality of cars at 45 the next movement. Fig. 10 illustrates a duplex arrangement of lift permitting of the raising and lowering of a plurality of cars at the same time. Fig. 11 illustrates diagrammatically an arrangement of multi-stage lift having several stages less than the

number of tracks which it is adapted to serve, and shows the lift in the successive positions to which it may be brought in raising and lowering the cars according to one convenient method.

55 Referring to Figs. 1 to 8 of the drawing A denotes the ground floor of a building in which the railway system is installed and B, C, D, E the first, second, third and fourth floors thereof.

60 a, b, c, d, e indicate the tracks on the floors A, B, C, D, E which tracks would, in the ordinary course, be suspended from the ceilings by means of suitable hangers; in practice I propose to use the ordinary double 65 rail tracks.

a', b', c', d' are the wells for the elevating lifts connecting the adjacent tracks a^2, b^2, c^2, d^2 indicating the respective lift platforms.

66 e' is the well of the return lift and e^2 e^2 70 indicate a series of platforms with which, as shown, the return lift is provided.

75 The wells for the elevating lifts are so constructed that they terminate beneath the ceiling of the story into which the lift rises, that is to say, the well of the lift a^2 terminates at the ceiling of the second story B and this renders it necessary that each lift platform should be suspended from the sides or bottom instead of from the top and also that 80 the safety gear should be arranged underneath the platform, there being insufficient head room to suspend the lift from the top. Such an arrangement of suspension is indicated in Figs. 3 and 4 in which f, f' indicate 85 the guide rods for the lift and f' the guides upon the lift.

86 g, g' are the ropes by means of which the lift is suspended and h, h ropes which carry counter-balance weights, not shown, these 90 ropes all passing over suitable pulleys arranged at the upper end of the well.

95 g', g' , Fig. 2, indicate the pulleys over which the winding ropes g pass, the pulleys over which the counter-balance ropes pass not being indicated. The ropes g, g 100 pass beneath the platform around sheaves g^o and are secured to the latter, as shown in Fig. 6, the said ropes being passed around the said sheaves from the opposite ends of

the platform, as shown in Fig. 4, while the ends of the said ropes are passed over the pulleys g' , g' at the top of the well and brought down and attached to a winding drum i , Fig. 2, arranged at the bottom of the well, the ends of one rope being first passed around guide pulleys i' so that the winding of the drum i in one direction will coil the ropes and when rotating in the opposite direction uncoil them.

j denotes an electric motor for operating the drum i .

The sheaves g^o are loosely mounted on a vertical spindle k , and at the lower end 15 of this spindle is loosely mounted a disk k' for a purpose hereinafter described.

Mounted beneath the lift platform on horizontal pivots l , adjacent to the guide rods f , are eccentrics l' , l' to which the ropes 20 h , h for the counter-balance weights are attached, these eccentrics being so arranged with relation to the guide rods f that under the tension due to the counter-balance weights they have a tendency to move 25 against the guide rods to grip the same. Each of these eccentrics l' is provided with an arm or lever m , the arms or levers of each pair of eccentrics l' being connected to the two links of a toggle n . The central 30 joint of each toggle n is connected by a rod n' to a pin n^2 on the disk k , so that the four toggles in connection with the four sets of eccentrics l' , l' will exert a thrust against the pins n^2 on the disk k' . This disk k' 35 is normally locked against rotation by a catch o pivoted to the platform and engaging a notch on the said disk, which catch also hangs in contact with cam surfaces o' , o' on the sheaves g^o , g^o . So long as the 40 ropes g , g are intact this catch o will remain in engagement with the disk k' and prevent any rotary movement thereof so that the gripping cams l' , l' will be held out of contact with the guide rods f . Should, 45 however, either of the lifting ropes g , g break, the part of such rope g which remains intact and connected to the sheave g^o , will, under the strain upon it, slightly rotate such sleeve, and owing to such rotation the catch o will be pushed outward by 50 one or the other of the cam surfaces o' and thereby be disengaged from the disk k' whereupon the said disk k' which has the strain of the counter-weights upon it, will 55 be slightly rotated and allow the toggle n , n to move sufficiently to allow the gripping eccentrics l' to come into contact with the guide rods to hold the lift against further movement. The gripping eccentrics l' , l' 60 are advantageously provided with serrated or roughened surfaces to afford a positive grip in case they come into action.

The numerals 1, 2, 3, etc., denote a number of cars which are distributed over the 65 several railway tracks and which are de-

signed to be successively raised from the ground floor to the first floor, from the first floor to the second floor, and so on to the fourth floor, and then returned to the ground floor. Each of these cars may be of any suitable construction and one of which, shown in Fig. 3 upon a lift platform, is provided with an electric motor p , Fig. 8, in connection with collecting brushes p' , p' which pick up current from a pair of conductor rails q , q , Fig. 4, a rheostat r controlled by a solenoid r' and with another pair of contacts s , s . It will be understood that the conductors q , q , are in connection with the electrical supply and always alive 80 and that the collecting brushes p' , p' are always bearing upon these conductors whatever may be the position of the car. It will also be understood that similar conductors q' are arranged upon the lift platforms, as 85 shown in Fig. 4, and that conductors q are arranged on each track so that when the lift is in its upper and lower positions it will be in circuit with such conductors.

Upon the lift and at predetermined points 90 upon the several tracks are arranged circuit closing bars t , which for convenience of description I will hereinafter refer to as "treadles" and which are operated electrically, as hereinafter described, the function of these treadles being to make or break the circuit of the solenoids r' on the cars. When the contacts s , s on a car are in contact with the treadle t , as shown in Fig. 8, the current from the conductors q , q will 100 energize the solenoid r' and retain the core in connection therewith in a position in which the arm of the rheostat r is out of circuit, so that the motor will not be operated. When, however, the treadle t is moved or 105 lowered away from the contacts s , s the solenoid r' becomes deenergized so that the weight of the said core will move the rheostat arm over the several contacts to throw in the motor to drive the car.

Each of the treadle bars t , as shown in the drawings, is mounted on rocking links t' , t' and has combined with it a pair of solenoids u , u' which are wound in opposite directions and which are respectively connected to two positive wires v , v' and to a common return wire v^2 . The two groups of solenoids u and u' of all the treadles on a floor are connected respectively to the wires v and v' and these wires together with the return wire v^2 terminate adjacent to the lift in spring contacts as at v^3 , while a similar set of contacts v^4 is connected with the supply wires, the positive supply wire, Fig. 4, being connected to the conductors v , v' .

Adjacent to the point where the positive conductor bifurcates, a branch v^5 is inserted which extends to two stud contacts v^6 on the lift in such a manner that as a car runs on to the lift a contact arm v^7 thereon 120

bridges the contacts v^6 , v^6 in passing and so allows the positive current to momentarily pass to the conductor v' to operate the several solenoids u' on the track to move the treadles t on the track and also the treadle on the lift from the dotted line position in Fig. 3 to the full line position to bridge the contacts s , s whereby the car motor will be stopped. The car under its momentum will 5 then continue to move forward until it comes in contact with the lift wall by means of a buffer or stop, not shown, at which point the contact arm v^7 will be adjacent to two other contacts w , w , Figs. 3, 4 and 5 on 10 the lift platform. It may be stated that the solenoids of the several treadles t on a floor are simultaneously supplied with current and that during the time that the lift platform is not between the contacts v^3 , v^4 the 15 solenoids of the several treadles will for the time being remain dead.

Each car is provided with gates or doors x , x , Figs. 3 and 5, which have to be opened and closed to allow passengers to enter and leave the car, and this operation of closing the doors after they have been opened is utilized for completing the lift circuit for starting the lift motor. This is accomplished by the following means, that is to 20 say, the doors x , x , if two doors are employed, are connected together by double links as shown so that they will open and close simultaneously and one of these doors x is provided with an arm or lug x' which 25 co-operates with a spring catch x^2 in connection with the contact lever v^7 in such a manner that on the closing of the said doors the said arm or projection x' by impinging against the catch x^2 will move the contact 30 arm v^7 to momentarily complete the circuit between the studs w , w , a spring x^3 in connection with the catch x^2 returning the lever v^7 to break the circuit immediately the arm x' disengages from the catch x^2 in passing. 35 In connection with the lift winding mechanism is a rheostat y which operates in the same manner as the rheostat r hereinbefore described, and also a reversing switch comprising two arms y' , y^2 arranged in conjunction with a bar y^3 which is constructed 40 to form the cores of two oppositely wound solenoids y^4 , y^5 . These solenoids y^4 , y^5 operate to move the switch which reverses the motor when the lift platform is in one or 45 the other of its extreme positions.

In combination with the winding drum i of the lift I arrange what I term a distance-switch, this distance-switch comprises a contact arm z which is driven by chain gear 50 from the shaft of the winding drum, the chain wheels bearing such ratio to one another that the movement of the lift platform from its lowest to its highest position or vice versa will move the said contact arm z from the position in contact with a 55 stud z' to another stud z^2 or vice versa. The arm z is in the circuit of the solenoid of the rheostat y and the contact studs z' , z^2 are respectively connected to terminals z^3 , z^4 . Adjacent to these terminals z^3 , z^4 are other 60 terminals z^5 , z^6 and on the bar y^3 are two contact pieces which serve to bridge the contact z^3 , z^5 and z^4 , z^6 respectively. The studs w , w on the lift platform are respectively in electrical connection with the solenoid y^4 and the return wire, and the solenoid y^5 is connected to a stud z^7 which forms one of a pair of contacts on the upper of the two floors between which the lift works, the other contact z^8 of the pair being connected with the return wire. 70

The operation of the described arrangement of switches and contacts is as follows. When the several parts are in the position shown in full lines in Fig. 2, the current will flow from the positive conductor through the solenoid of the rheostat y and the arm z of the distance switch, the contacts z' of the said switch and the contact z^3 , z^5 , which are bridged by the bar y^3 80 to the return wire so that the lift will remain inoperative. Immediately, however, by the closing of the car gates x , the contacts w , w are momentarily bridged, as before described, a current from the positive conductor will flow through the solenoid coil y^4 and this momentary energizing of the coil y^4 will serve to move the bar y^3 to 85 operate the reversing switch from the position shown in full lines in Fig. 2 to the position indicated by the dotted lines. When this takes place the circuit of the solenoid of the rheostat y is broken so that the core by its weight serves to operate the rheostat arm to switch in the motor; the movement of the bar y^3 that operates the reversing switch 90 also breaks the circuit between the contacts z^3 , z^5 and closes the circuit between the contacts z^4 , z^6 so that when, owing to the operation of the motor, the contact arm z' comes 95 into contact with the stud z^2 , the solenoid of the rheostat y is again energized so that the rheostat arm is moved to cut out the motor when the lift will come to rest in its 100 uppermost position. 110

The return lift, as shown, consists of a series of cages or platforms e^2 carried between two endless chains running around suitable sprocket wheels or drums which are operated by an electric motor Z . This motor is arranged in conjunction with stopping and starting mechanism in such a manner that it can only operate to move the lift when a car has been running on to one platform at the upper end of the lift and another car moved off a platform at the lower end of the lift. For this purpose the stopping and starting mechanism and the electric circuits are arranged as follows. The motor Z has combined with it a sole- 120 125 130

noid controlled rheostat Y which operates in the same manner as the rheostat γ in connection with the ascending lift motors. In the circuit of the rheostat solenoid coil are 5 arranged two pairs of contacts X , X' the members of each pair being normally in contact. In connection with these pairs of contacts X , X' are solenoids W , W' , the cores of which solenoids are connected to a 10 cross head V which has also connected to it the core of another solenoid U. Upon the cross head V are wedges T, T' of insulating material designed to enter between the contacts X , X' to separate them and the break 15 of circuit in which they are situated.

Adjacent to the receiving platform at the upper end of the return lift are arranged two contacts S which, when a car runs on to the said platform, will be bridged by a suitable 20 contact on the car. The solenoid W is in the circuit with the contacts S, so that when the latter are bridged, a current will flow from the positive main through the solenoid W and lift its core so that the 25 wedge T enters between the contacts X and breaks the circuit of the rheostat coil Y at this point, while at the same time the current can continue to flow through the said coil to the contacts X' .

30 Adjacent to the discharging platform on the floor A, but outside the lift, are two contacts R which are designed to be bridged by the contact on the car which bridges the contacts S. The solenoid W' is included in 35 the circuit in which these contacts R are placed so that when the said contacts are bridged (by the passing movement of the bar) the solenoid W' will be energized to lift the cross head V to separate the contacts X' by means of the insulating wedge T' . When the contacts X , X' are both 40 broken in the manner described the coil of the rheostat Y will become dead, so that the rheostat will operate to switch in the motor 45 Z, the car upon the receiving platform being lowered and the next car at the lower end being brought into the discharging position by the operation of the lift.

50 In connection with the return lift is a distance-switch Q provided with several pairs of contacts P , P' with which the switch arm O is designed to successively make contact. This arrangement of several pairs of contacts, however, is of no importance but is 55 simply used as a most convenient method in order to avoid the necessity for having to drive the arm O at too great a speed, during each step movement of the lift. The contacts P , P' are in the circuit of the solenoid of the rheostat Y and the arm O is connected to the positive main conductor, the contacts P' being in the circuit of the solenoid U.

60 It will thus be seen that when the return lift starts to lower a car the arm O which is

in contact with a contact P will be moved into contact with the contact P' , with the result that a current will momentarily be caused to pass through the solenoid U and thereby pull down the cross head V to withdraw the wedges from the contacts X , X' , so that the circuit of the solenoid of the rheostat Y will be closed at the contacts X , X' , but as it has already been broken by the arm O leaving the contact P the said solenoid is not reenergized. The downward movement of the lift will continue until the arm O comes into contact with the next contact P, whereupon current will be supplied to the solenoid of the rheostat Y through 70 the contacts X , X' which have been previously closed, as described, the solenoid being thereby energized to operate the rheostat to stop the motor Z.

In illustrating my invention I have shown 75 a number of cars on each floor track, but it will be understood that this number will vary according to circumstances, as the system can be worked with a smaller number of cars, for instance, one upon each floor. 80 Where more than one car is employed then a series of treads t will have to be provided for stopping all the cars upon a floor, as shown, at predetermined points during 85 the time that the lift is raising a car from one floor to another floor.

The general operation of the apparatus is as follows: Assuming the lift a^2 on the floor A to have just been lowered so that the treads have been lowered to break the circuit 90 of the solenoid r' and start the motor as hereinbefore described (and also of any other cars, say the cars 2, 3 and 4 on the floor A) the car 1 will then run forward on to the lift a^2 and the cars 2, 3, 4 and 5, take 95 the places of the cars 1, 2, 3 and 4 respectively while at the same time a car 6 on the upper floor will run on to the return lift, the cars 7 and 8 on the upper floor taking the positions of the cars 6 and 7, respectively. 100 As the car 1 passes over the contacts v^6 it causes the raising of the treads t to bridge the contacts s on the several cars and stops the latter from further movement. The passengers now enter the car on the 115 lift and when an attendant closes the car doors w the contacts w , are bridged, as before described, whereby the motor will be started and raise the lift platform a^2 to the floor B where it will be automatically 120 stopped by the operation of the distance switch arm z hereinbefore described. Assuming the platform b^3 which is raised from the floor B to the floor C to be in its lowermost position, as indicated in the drawing, 125 the presence of the lift platform a^2 will complete the circuit of the treads t on the floor B so that the said treads will be lowered and allow the car 9 to enter the lift b^2 , and the car 1 to take the position of the car 11, 130

which with the cars 9 and 10 at the same time will move forward one section or from one treadle to another. Should the lift b^2 not be in its lowest position on the floor B when the lift a^2 reaches the floor B then the car 1 will remain on the lift a^2 until such time as the lift b^2 is in the said position. The same operation is repeated as a car passes from the floor C to the floor D and from the floor D to the floor E, while the cars from the upper floor E will be moved on to the lift at the same rate as they are raised from the track a .

The circuits of the treadles t on the tracks b, c, d are independent of one another and are operated solely by the respective lifts, but the tracks a on the floor A and the tracks e on the floor E are interconnected in the manner indicated so that when the treadles t of the track a are operated, the treadles on the floor E and on the lift will be correspondingly operated, so that as a car from the track a runs on to the lift a^2 a car from the track e will run on to the return lift and a car be discharged from the lower end of such return lift on to the track a .

In order that a car shall be prevented from running off its track into the well of its raising lift if by any chance it shall from any cause be moving along the track before the lift is in position to receive it I provide mechanism such as that indicated in Figs. 3 and 4 and advantageously comprising an arm N designed to be placed across and form an obstruction on one of the track rails, as indicated by the dotted lines in Fig. 4, by a spring operated rod M, the said rod being connected to a bell crank L which is operated by the lift as shown to remove the arm when the said lift is in line with the track.

In lieu of employing a plurality of elevating lifts each operating in its own lift well as above described, I may employ an arrangement of multi-stage lifts such as those shown in Figs. 9, 10 and 11.

In accordance with the construction requiring only single lift well, Fig. 9, the well is located more or less centrally of the building, emporium or the like and the tracks a, b, c, d, e , and a^2, b^2, c^2, d^2, e for the various floors A, B, C, D, E extend from both sides of the well the tracks being arranged so that except that e for the uppermost floor E a car passing on to any track from a lift may return to the point of departure. In this well is disposed a lift provided with a number of superposed platforms e^2 or stages suitably one less in number than the number of tracks to be served, such platforms e^2 being disposed at a distance from one another corresponding to the distance apart of the corresponding tracks of the building or the like so that each platform may be brought into a position opposite a track at one time. With this construction, the lift need only be

moved up and down an amount corresponding to the distance between two tracks and in such upward movement a car on each platform can be raised to the track above and then passed from its platform on to this track in this position. Cars returning from the track at the same level on the other side of the building may then be passed on to the platform and the lift moved down to its former position thereby bringing the returning cars opposite the track lower down, whence they can be passed on to the respective tracks intended for their reception. Before the next upward movement the cars to be elevated are returned to the platforms intended for them and each car is then raised to the next track, passed off the lifts, the returning cars being moved on to the platforms and all are lowered simultaneously to the next lower track.

In another form, Fig. 10, I arrange the tracks in a manner similar to that above described and arrange in the lift well a pair of multi stage lifts preferably connected with one another by a rope or the like passing over a pulley in such manner that one moves up as the other moves down, these lifts being provided with a number of superposed platforms or stages suitably one less in number than the number of floors in the building, the platforms or stages being so disposed that each platform will come into a position opposite a track at one time. One of these lifts X is used as an elevating lift and the other Y as a return lift. The cars are supplied to and removed from the tracks for the respective floors of the building, emporium or the like by alternately raising and lowering each lift of the double lift through an amount corresponding to the distance between two tracks. In this way a car on each platform is raised on the upward movement of the elevating lift to the level of the next track and can be passed around the one side of the building while each car loaded on the platforms of the return lift moves down to the next lower track on that side of the building or the like and can be passed around the same. Each car can thus pass successively to each floor on one side of the building, pass around the top floor and on the return movement can pass around each floor in the other side of the building.

In lieu of providing a lift with sufficient platforms that it need only be raised and lowered by the amount of one track I may provide a lift with fewer platforms and operate and load the lift in such manner that the cars can be carried to and from all the tracks in the building although such cars need not be circulated around successive tracks in succession. For instance, Fig. 11 shows a lift with three stages for use in a five story building; and shows the successive positions into which the lift may be brought in oper-

ating it according to a suitable method under which in the upward movement only the uppermost and lowermost stages will carry cars and the lift will pass a track on the 5 upward movement but will stop opposite all tracks on the downward movement.

It is to be understood that my invention is not confined to the construction and arrangement of parts which I have described, 10 as other arrangements for operating the cars and controlling the lifts can be employed without departing from the nature of such invention.

Having described my invention, I declare 15 that what I claim and desire to secure by Letters Patent of the United States is:—

1. A railway system for use in buildings comprising a series of tracks on different floors with cars arranged to travel around 20 such tracks, a series of lift wells each connecting with two tracks, a series of lifts operating within said lift wells for conveying the cars successively from one of said tracks to the other of said tracks, a lift well extending from the uppermost track to the 25 lowermost track of the building and a lift operating within the said well, substantially as and for the purpose set forth.

2. In a railway system for use in buildings 30 for conveying passengers around the floors of said building, the combination with a lift, electrical elevating and lowering mechanism for said lift, tracks on the floors between which the lift operates, and an 35 electrically propelled car on each track, of means coöperating with said lift for causing the car on the lowermost of said tracks to enter the lift in the lowermost position of said lift, and for causing the other cars to 40 travel over a portion of track, means for stopping a car when it has entered the lift, means for causing the closing of doors or the like to actuate the lift raising mechanism to raise the lift, and means for actuating the lift lowering mechanism as the 45 car passes off the lift substantially as set forth.

3. In a railway system for use in buildings, the combination with a lift, electrical 50 elevating and lowering mechanism for said lift, tracks on the floors between which the lift operates, and an electrically propelled car on each track, of means coöperating with said lift for causing the car on the 55 lowermost of said tracks to enter the lift in the lowermost position of said lift, and for causing the other car or cars to travel over a portion of track, means for stopping a car when it has entered the lift, means for 60 causing the closing of doors or the like to actuate the lift raising mechanism to raise the lift and means for actuating the lift lowering mechanism as the car passes off the lift, a lift well extending from the uppermost to the lowermost track, a lift with- 65

in said well and means for controlling the speed of said lift substantially as and for the purpose set forth.

4. A railway system for use in buildings 70 designed for conveying passengers in cars around the floors or certain of the floors of such buildings, the said system comprising a track on each floor around which a car is to traverse, and a lift for conveying a car from one of such tracks to another of said tracks, contacting means on the cars, contact devices adapted to coöperate with said contacting means, and means for moving said contact devices out of contact with said contacting means substantially as and for 75 the purpose set forth.

5. A railway system for use in buildings 80 designed for conveying passengers around the floors or certain of the floors of such buildings, the said system comprising a lift 85 well disposed substantially centrally of the building, a track extending from each side of said lift well on each of the floors of said building around which a car is to traverse, and a lift adapted to operate within said lift well for conveying a car from one track to another, said lift provided with a plurality of stages, said stages disposed apart distances equal to the distances apart of said tracks, said lift serving to raise at a 90 time a plurality of cars from tracks to other tracks and to lower a plurality of cars from tracks to other tracks at a time.

6. A railway system for use in buildings 95 designed for conveying passengers around the floors or certain of the floors of such buildings, the said system comprising a lift 100 well disposed substantially centrally of the building, a track extending from each side of said lift well on each of the floors of said building around which a car is to traverse, and a lift adapted to operate within said lift well for conveying a car from one track to another, said lift provided with a plurality of stages, said stages one less in number than the number of said tracks, said 105 stages disposed apart distances equal to the distances apart of said tracks, said lift serving to raise at a time a plurality of cars each from its track to the next and to lower 110 a plurality of cars each from its track to the next at a time.

7. A railway system for use in buildings 115 designed for conveying passengers around the floors or certain of the floors of such buildings, the said system comprising a lift 120 well disposed substantially centrally of the building, a track extending from each side of said lift well on each of the floors of said building around which a car is to traverse, 125 and a pair of connected lifts adapted to operate within said lift well for conveying cars from tracks on one level to tracks on another level, said lifts each provided with a plurality of stages, said stages of each lift 130

being one less in number than the number of said tracks, said stages disposed apart distances equal to the distances apart of said tracks, said lifts serving to raise a plurality of cars each from its track to the next at a time and to lower a plurality of cars from tracks to other tracks at the same time.

In testimony whereof I have signed my name to this specification in the presence of 10 two subscribing witnesses.

BERNARR MACFADDEN.
